UNITED STATES PATENT OFFICE

2,380,302

DOOR OPERATOR

William A. Geiger, Chicago, Ill., assignor to William P. Sidley, M. F. Back, Albert P. Withall, Edwin C. Austin, and George A. Johnson, all of Chicago, Ill., and Alice T. Miner, Chazy, N. Y., as trustees of The William H. Miner Foundation

Application January 6, 1944, Serial No. 517,176

3 Claims. (Cl. 292—218)

My invention relates to improvements in door operators, more particularly, but not necessarily, adapted for use in connection with refrigerator car doors.

One of the objects of the invention is to provide a rotary operating means for forcing the doors of refrigerator cars either open or tightly closed, in which end members on a rotary bar have camming engagement with keepers on the car and in which the end members and rotary bar are interlocked in assembled relation by bearing brackets. whereby construction is simplified and cost of manufacture is materially reduced by the elimination of the usual labor involved in fixedly securing the end members to the bar.

A further object is to provide a door operating means in which bearing brackets are utilized to hold the end members and rotary bar in assembled relation within the bearings.

A further object is to provide interengaging lugs and seats within the bearings and on the end members and the rotary operating bar whereby the assembling of the parts interlocks the parts in operating condition without further adjustment or fastening means.

Other objects of the invention will appear from the following description and claims in connection with the accompanying drawing which illustrates one embodiment of the invention.

Referring to the drawing,

Fig. 1 is a view in elevation of a wall of a refrigerator car with a pair of hinged doors mounted thereon and illustrating the improved door operating structure in connection therewith;

Fig. 2 is an enlarged sectional view of the lower end portion of the operating means illustrating the interlocking means between the operating bar, the end member and the bearing therefor;

Fig. 3 is a horizontal section substantially on the line 3—3 of Fig. 2;

Fig. 4 is a view in elevation of the end crank member and operation bar in assembled relation;

Fig. 5 is a sectional view similar to Fig. 2 but illustrating a modified form of interlock between the members; and

Fig. 6 is a detail view of the interlocking beads or lugs shown in Fig. 5.

Referring to the drawing, the car wall A has the usual opening 1 closed by a pair of hinged doors B and C which are of the usual design having beveled edges which cooperate with the correspondingly beveled edges of the door frame. In the usual refrigerator door construction, the meeting edges of the doors are beveled so that the door B is first closed and the edge of door C

overlaps the edge of door B. The door B is provided at its lower inner corner with a wear plate 2 which is engaged by a pivoted latch 3, the purpose of which is to hold the door B closed while the door C is being opened by the door operating mechanism.

The door operating mechanism comprises generally the vertical rotary bar D having end crank or cam members 5 mounted in bearing brackets E and adapted to cooperate with upper and lower keepers 6 on the door frame. A suitable operating lever F is pivotally secured to the operator bar D for the purpose of rotating the bar on its axis, the lever being normally locked with the doors in closed position by means of the usual seal latch means 7. The top and bottom keepers 6 are of the usual type having cam slots 8 within which the cranks or offset members 9 of the end members 5 are adapted to engage to force the door partly open or tightly closed.

The rotary bar D is of substantially rectangular cross section throughout its length and has its edges curved on a radius to fit it for rotation in the upper and lower bearing brackets E, the rounded edges of the lower end portion of the bar being indicated by 10 in Fig. 3. As shown in Figs. 2, 3 and 4, the rounded edges 10 of the bar have notches or seats 11 which are transversely aligned and are located preferably about midway of that portion of the bar which lies within the vertical length of the bearing.

The top and bottom end members 5 are similar in design and each comprises a forked or divided portion 12 which embraces opposite sides of the flat end portion of the bar so that when the bar and end member are assembled a suitable connection is made by which the bar can rotate the end member. The spaced arms or members 13 forming the forked portion 12 have notches 14 in their edges, which register with the notches 11 in the bar. The upper and lower ends of the forked portion are provided with enlargements 15 which are made cylindrical to fit the bearing portions of the bearing bracket E.

The bearing brackets E, which are secured to the door adjacent the top and bottom ends thereof, are of two-piece construction, each comprising a back or base plate 16 and a cover plate. The back plate 16 has bearing projections 18 at its upper and lower ends, which present bearing surfaces for the enlargements 15 of the end members. The cover plate is in the form of a semi-cylindrical portion 19 which embraces half of the enlargements 15 to provide bearing surfaces therefor. These bearing surfaces and those

of the base projections 18 are thus complementary and provide bearings for the major portion of the circumference of the enlargements. On the interior wall of cylindrical portion 19, an integral semi-annular bead or lug 20 is provided which is located to register with the slots or seats 11 and 14 of the bar and end member when the parts are assembled, and to engage in and interlock with said notches and thereby maintain the end member, bar and bearing against relative endwise displacement. The bead or lug is preferably semi-cylindrical in section and extends toward the back plate beyond the diameter of the end member forked portion so that it actually engages the slots for more than half the circumference thereof.

The back plate and the cover plate have lateral flanges or ears 21 and 22 respectively, which are overlapped and secured to the car door by means of the bolts 23.

In Figs. 5 and 6 a modified interlocking structure is shown. In this form the wall 19 of the bracket cover plate is formed outwardly to provide an internal groove 24. Nibs or lugs 25 are formed on the edges of the bar D to register with said internal groove 24 and to cooperate therewith in interlocking the bar and bearing member. In like manner, the edges of the fork member 13 of the end member are provided with lugs or nibs 26 in registration and for cooperation with groove 24 of the bearing member.

I claim:

1. In a device of the character described, the combination of a bearing bracket comprising a base member and a cover member forming when assembled a cylindrical bearing portion, an end member rotatably positioned in said bearing portion, an operating bar extending into said bear-

ing portion in overlapping telescoped relation with said end member, and interlocking means within the bearing portion of the cover member and between the cover member the end member and bar for holding the bearing bracket, end member and bar against relative endwise displacement.

2. In a device of the class described, the combination of a bearing bracket comprising superposed members having a cylindrical portion forming an elongated bearing, the wall of said cylindrical portion having an internal semi-annular bead, an end member rotatably positioned in said bearing, said end member having an elongated lengthwise slot therein opening laterally, and having notches in its periphery registering with and engaging the said bead, and an operating bar seated in said lengthwise slot in said end member and having notches in its edges registering with and engaging said bead, said bead and notches locking said end member and bar against endwise displacement in either direction in said bearing bracket.

3. In a device of the class described, the combination of a bearing bracket comprising superposed members having a cylindrical portion forming an elongated bearing, the wall of said cylindrical portion having an internal semi-annular groove, an end member rotatably positioned in said bearing, said end member having an elongated lengthwise slot therein opening laterally, and having lugs on each side of said slot registering with and engaging said groove, and an operating bar seated in said lengthwise slot in said end member and having lugs on its edges registering with and engaging said groove.

WILLIAM A. GEIGER.
